UNITED STATES PATENT OFFICE.

JOSEPH E. G. ALEXANDER, OF PHILADELPHIA, PENNSYLVANIA.

AEROPLANE.

1,081,420.

Specification of Letters Patent.

Patented Dec. 16, 1913.

Application filed July 23, 1912. Serial No. 711,074.

To all whom it may concern:

Be it known that I, JOSEPH E. G. ALEXANDER, a subject of the King of Great Britain, residing at Philadelphia, in the county of Philadelphia and State of Pennsylvania, have invented certain new and useful Improvements in Aeroplanes, of which the following is a specification.

My invention relates to improvements in aeroplanes, the object of the invention being to provide an aeroplane of the biplane type with improved steering mechanism, in which steering means are provided in front of the main planes in combination with ailerons.

A further object is to provide an improved construction of biplane having ailerons thereon, and provided with a fore-and-aft frame having fixed horizontal and vertical rudders at its rear end and movable horizontal and vertical rudders at its forward end, and provide improved means for controlling the movement of the forward rudders and the ailerons.

A further object is to provide an aeroplane with improved landing means which normally hold the plane at an incline so as to readily take the air and give a quick lift in starting.

With these and other objects in view, the invention consists in certain novel features of construction and combinations and arrangements of parts as will be more fully hereinafter described and pointed out in the claim.

In the accompanying drawings: Figure 1 is a top plan view illustrating my improvements. Fig. 2 is a view in side elevation. Fig. 3 is a fragmentary sectional elevation on an enlarged scale illustrating the aileron controlling treadles. Fig. 4 is a similar view illustrating the vertical and horizontal rudder control. Figs. 5, and 6 are fragmentary views in elevation at right angles to each other illustrating the connection between the front horizontal rudder and its controlling arm. Fig. 7 is a fragmentary view in section illustrating the pivotal connection of the steering lever with its supporting bar, and Fig. 8 is a fragmentary view in elevation at right angles to Fig. 3.

1, 1, represent the parallel main planes connected by uprights 2 which are secured to the fore-and-aft frame 3, and these up-

rights 2 at the center of the aeroplane, extend below the lower main plane and are fixed to curved runners 4 constituting the lower bars of a landing frame. The front ends of these bars 4 are curved and their rear ends extend upwardly and are adapted to contact with the ground, while wheels 5 are provided at the intersection of the forward uprights 2 and the runners to permit the biplane to roll readily over the ground in starting and alighting. At the same time, these wheels 5 hold the fore-and-aft frame at an incline as seen most clearly in Fig. 2, so that the ship will readily take the air in starting. At the front and rear of the fore-and-aft frame 3 on the lower bars thereof, upwardly bent runners 6 are provided which are adapted to strike the ground if the machine is unduly tilted, and cause the same to assume its normal position with the wheels 5 on the ground. At the front end of the fore-and-aft frame 3, a horizontal steering rudder 7 is located, and back of the same, a vertical steering rudder 8 is mounted to swing. At the rear end of the fore-and-aft frame, a fixed horizontal rudder 9 is secured and a fixed vertical rudder 10 is secured. These fixed rudders 9 and 10 nicely balance the movable rudders 7 and 8, and insure a steady device in the air.

The runners 4 are connected to the uprights 2 by diagonal braces 11, and these braces 11 are connected to the lower members of the fore-and-aft frame by rods 12. These rods 12 are connected by a transverse bar 13 on which a post 14 is mounted. A horizontal bar 15 is provided with a central bearing 16 mounted to turn on post 14, and on the ends of this bar 15, foot rests 17 are secured. These foot rests and bar constitute an oscillating treadle and said foot rests are connected by wires 18 with ailerons 19 supported between the planes 1, 1, as is customary with machines of this character. The pedals are connected to the ailerons on the respective sides of the device, that is, the pedal on the left is connected to the left hand aileron and the pedal on the right to the right hand aileron. When the device is turning to either the right or left there is a tendency for that side of the machine in the direction toward which it is turning, to drop and therefore the aileron on said side should be operated to right the machine.

As the machine tilts in turning, it is but natural to depress the foot upon the lowermost side, and in doing so the operator, with a machine constructed as described, will naturally operate the proper aileron.

Three inclined bars 20 connect the bars 12 with the main frame, and the central one of these bars serves as a support for the steering post 21. This steering post is bifurcated at its lower end as shown at 22, straddles the flattened portion of one of the bars 20, and is pivotally connected to said bar by a bolt 23.

The horizontal steering rudder 7 is provided with a crank arm 24, and the latter is connected by a rod 25 with post 21, so that the fore-and-aft movement of post 21 serves to move the rudder 7. The vertical rudder 8, at its rear end, is connected by wires 26 with the rotary hub 27 of a steering wheel 28 on the upper end of post 21. It will thus be seen that by turning the steering wheel 28, the rudder 8 is swung to right and left, and by moving the post 21, fore-and-aft, the rudder 7 is tilted.

While my aeroplane is not limited to any construction or location of engine, I have illustrated an engine 29 diagrammatically between the main planes 1, 1, and having a rearwardly projecting shaft 30 with a propeller 31 on its rear end. The operator's seat 32 is located in close proximity to the post 21, and treadle 15, and this post, treadle, and seat are extended forwardly beyond the main planes and to one side of the center of the fore-and-aft frame so that the operator will be away from the engine and from under the main planes. This is a desirable location in the event of accident,

as the operator can readily free himself from the planes.

Various slight changes might be made in the general form and arrangement of parts described without departing from my invention, and hence I do not limit myself to the precise details set forth, but consider myself at liberty to make such changes and alterations as fairly fall within the spirit and scope of the appended claim.

Having thus described my invention, what I claim as new and desire to secure by Letters Patent is:

An aeroplane comprising two main planes, a fore-and-aft frame extending in front and rear of the main planes, a horizontal plane at the forward end of said frame, a vertical plane mounted in the said frame and in rear of the horizontal plane, a second horizontal plane rigidly mounted near the rear end of the fore-and-aft frame, a second vertical plane rigidly mounted in rear of the said second horizontal plane, ailerons mounted between the main planes, a post, a bar mounted between its ends on the post, vertical foot rests on the ends of the bar, and flexible devices connecting the right and left foot rests and the right and left ailerons respectively, whereby an oscillating movement of the bar operates the ailerons, substantially as described.

In testimony whereof I have signed my name to this specification in the presence of two subscribing witnesses.

JOSEPH E. G. ALEXANDER.
